UNITED STATES PATENT OFFICE.

JOSEPH S. DUNCAN, OF CHICAGO, ILLINOIS.

PRINTING AND ADDRESSING MACHINE.

Application filed October 2, 1916. Serial No. 123,233.

To all whom it may concern:

Be it known that I, JOSEPH S. DUNCAN, a citizen of the United States, residing at Chicago, in the county of Cook and State 5 of Illinois, have invented certain new and useful Improvements in Printing and Addressing Machines, of which the following is a specification.

The primary object of my invention is to 10 provide a compact and substantial machine of relatively simple construction for printing, in successive operations, from a single body form and successively changing address forms to produce any desired number 15 of individually addressed letters having the same subject-matter.

Another important object of the invention is to provide a machine which can be operated by hand or by power embodying 20 mechanisms for automatically and at the proper time feeding the paper to and removing it from printing position, feeding the ribbon intermittently, and feeding the address devices into and out of printing position.

Further objects of the invention are to provide simple means for adjusting the platen frame relative to the bed frame to vary the pressure of the platen upon the 30 printing devices; to provide for easily removing the ribbon from printing position to permit access to the bed for changing the body form; to enable the magazine which holds the address devices to be readily removed, permitting the machine to be operated without the use of address devices, and to provide various combinations of elements adapted to perform the different functions which are essential to a successful 35 commercial machine of this character, all of which will be fully pointed out hereinafter in connection with the accompanying drawings, illustrating the preferred embodiment of my invention, in which—

40 Fig. 1 is an elevation of the side of the machine from which the paper is fed thereto;

Fig. 2 is a front elevation of the machine with the ribbon mechanism withdrawn from 45 its normal position;

Fig. 3 is a plan view of the machine;

Fig. 4 is a vertical section on the line 4-4 of Fig. 1;

Fig. 5 is an enlarged detail in section on 50 the line 5-5 of Fig. 4;

Fig. 6 is an enlarged detail in elevation of a portion of the ribbon mechanism;

Fig. 7 is a vertical section on the line 7-7 of Fig. 1;

Fig. 8 is a detail view of a portion of 60 the operating mechanism;

Fig. 9 is a detail in perspective of a portion of the operating mechanism illustrating the means for disconnecting the plate feeding mechanism therefrom;

Fig. 10 is a vertical section on the line 10-10 of Fig. 2;

Fig. 11 is a vertical section on the line 11-11 of Fig. 7;

Fig. 12 is a vertical section on the line 12-12 of Fig. 7;

Fig. 13 is a vertical section on the line 13-13 of Fig. 7;

Fig. 14 is a horizontal section on the line 14-14 of Fig. 7;

Fig. 15 is an enlarged detail in vertical section on the line 15-15 of Fig. 3, illustrating the normal position of the platen with the feed fingers gripping a fresh sheet of paper preparatory to placing it upon the 80 bed and the discharge fingers gripping the printed sheet preparatory to the removal thereof;

Fig. 16 is a similar view illustrating the mechanism at the beginning of the return 85 stroke with the sheet of paper disposed upon the bed;

Fig. 17 is an enlarged detail in vertical section on the line 17-17 of Fig. 3, illustrating the normal position of the means for 90 feeding the address plates;

Fig. 18 is a vertical section on the line 18-18 of Fig. 17; and

Fig. 19 is a view similar to Fig. 17, illustrating the position of the parts at the end 95 of the feeding stroke;

Referring to the drawing 5 indicates the bed frame of any suitable form and construction to support the various parts of the mechanism and particularly the bed 100 plate 6 upon which the body form 7 bearing a plurality of lines of type is secured. A platen guiding frame 8 is disposed above the bed frame 5 and supported thereon by springs 9 (Fig. 13) which permit movement 105 of the platen guiding frame 8 toward and from the bed frame 5. Supported in suitable bearings in the bed frame 5 and disposed longitudinally and at either side thereof are a pair of shafts 10 (Fig. 7) hav- 110

ing eccentric pins 11 (Fig. 13) projecting from their extremities upon which are pivoted members 12 projecting upwardly through suitable openings in the bed frame 5 and the platen guiding frame 8. The members 12 prevent relative longitudinal or transverse movement of the bed and platen guiding frames. The upper ends of the members 12 are engaged by screws 13, the heads of which rest on washers 14 spanning the openings into which the members 12 project so that by individually rotating the screws 13 at the corners of the frame, the platen guiding frame 8 may be drawn 10 downwardly against the springs 9 and toward the bed frame 5. Substantially midway of their length the shafts 10 are provided with arms 15 connected by a link 16. A screw 18 (Fig. 7) having a knurled head 20 is mounted in the platen guiding frame 8 at the feed side of the machine and threadly engages a pin 20 pivotally mounted in a yoke 21 on the link 16. By operating the screw 18 through its knurled head 25 19 the ink 16 may be moved transversely of the machine thereby rocking the shafts 10 to simultaneously draw the platen guiding frame 8 against the springs 9 toward the bed guiding frame 5 or to permit the 30 springs 9 to lift the platen frame 8 from the bed frame 5. Thus the platen guiding frame 8 may be adjusted toward and from the bed frame 5 to regulate the distance of the platen from the body form 7 as more 35 fully set forth hereafter. In setting up the machine the platen guiding frame 8 is adjusted with respect to the bed frame 5 by operating the screws 13 at the four corners to insure movement of the platen parallel 40 to the bed plate 6.

The platen guiding frame 8 is provided with a pair of supports 22 (Figs. 1, 3,) having tracks 23 angularly disposed with respect to the lines of type on the body form 7 to receive rollers 24 rotatably mounted on the platen carriage 25. The platen carriage 25 is thus readily movable transversely of the machine and, as will be noted by reference to Fig. 3, the movement is at an angle 45 to the direction of the lines of type on the body form 7. A platen 26 is rotatably mounted in links 27 (Fig. 15) pivotally supported in lugs 28 depending from the platen carriage 25 and is provided adjacent its ends 50 with grooved anti-friction rollers 29 (Fig. 13). A shaft 30, disposed above and extending longitudinally of the platen 26, is supported by links 31 pivotally mounted on arms 32 secured to a shaft 33 which is rotatably mounted on the platen carriage 25. The shaft 30 is provided at its extremities with flanged anti-friction rollers 34, the flanges of which bear against tracks 35 on the supports 22. The flanges on the rollers

34 also enter the grooves on the rollers 29 and 65 the rollers 29 engage the rollers 34 on either side of the flanges thereon. The rollers 29 and 34 are so proportioned with reference to the platen 26 that as the platen 26 rotates on the printing surface the rollers move 70 along their tracks 35 without slipping and without any drag on the printing surface.

Referring to Figs. 15 and 16 it will be readily seen that the anti-friction rollers 34 are movable over the grooved roller 29 to depress and hold the platen in proper position to cause an impression to be taken in the manner hereinafter described or permitted to be lifted by springs 36 (Fig. 4) secured to the links 27 and to the platen carriage 25. 75 To automatically rock the shaft 33 and thereby cause the platen 26 to move toward the bed plate 6 I provide pins 37 and 38 (Figs. 3 and 4) on the supports 22 and dogs 39 and 40 on the shaft 33. When the platen carriage 25 approaches its normal position, as indicated in Figs. 3, 4 and 15, the dog 40 engages the pin 38, rocking the shaft 33 and swinging the anti-friction rollers 34 out of the vertical line through the axis of the 80 platen 26 so that the latter is drawn upwardly by the springs 36. When the platen frame 25 reaches the end of its forward movement to the right, viewing Fig. 3, the dog 39 engages the pin 37 to rock the shaft 90 33 and thereby move the anti-friction rollers 34 rearwardly on grooved rollers 29 to press the platen downwardly into printing position and as the platen frame 25 returns to its normal position an impression will be 95 taken. 100

A feed table frame 41 (Fig. 4) is hingedly connected to the feed side of the machine, being supported by a pair of toggle links 42 pivotally connected at 43 and 44 to the feed table frame 41 and the bed frame 5, respectively, and to each other at 46. A spring 47 prevents the toggle from breaking when the feed table frame 41 is disposed in normal position. A feed table 48 is mounted on the feed table frame 41 and is adjustable longitudinally of the machine. A pair of guides 49 are supported on a bar 50 extending across the feed table 48 and supported on brackets 51 formed on the feed table frame 110 41. The function of the guides 49 is to limit the forward movement of the paper as it is fed from the feed table 48 to the machine. The platen carriage 25 is provided with a depending portion 52 (Figs. 15, 16) having 115 a ledge 53 adapted to pass beneath the guides 49. Rotatably mounted on the depending portion 52 is a shaft 54 carrying a plurality of feed fingers 55 adapted to cooperate with the ledge 53 to grip a sheet of paper. A spring 56 secured to a pin 57 on the depending portion 52 of the platen carriage 25 and to a pin 58 secured to the 120 125

shaft 54 normally holds the fingers 55 in engagement with the ledge 53. At the end of one of the supports 22 a dog 59 is pivotally mounted and provided with a pin 60 which is disposed in the path of an arm 61 secured to the shaft 54. The arm 61 is so formed that as the platen carriage 25 approaches the limit of its movement to the left (Fig. 15) it rides over the pin 60, rocking the shaft 10 54 and thereby lifting the fingers 55 sufficiently to pass over the edge of a sheet of paper disposed against the guides 49. When the arm 61 has passed the pin 60 the spring 56 returns the fingers 55 to normal position 15 gripping the paper and depressing it sufficiently to disengage it from the stops 49. As the platen carriage returns the arm 61 rides under the pin 60 lifting the dog 59. Downward movement of the pin 60 is limited by a pin 62 on the support 22 which is engaged by a lug 63 on the dog 59.

The paper, being firmly gripped by the fingers 55, is drawn from the feed table 48 under stops 49 and across the bed plate 6 25 until it engages stops 64 arranged adjacent the discharge side of the machine. The continued movement of the platen carriage 25 frees the paper from the fingers 55 and the paper remains in impression-receiving position during the return stroke of the platen carriage.

The sheet bearing the impression is removed as the platen carriage 25 advances to dispose a fresh sheet above the bed plate 35 6. To accomplish the removal I provide a shaft 65 rotatably mounted in suitable bearings in the bed frame 5 to which a pair of arms 66 having fingers 67 are secured. Pivotally mounted at 68 on the arms 66 are 40 fingers 69 adapted to cooperate with the fingers 67 to grip the sheet of paper as indicated in Fig. 15. Springs 70, secured at 71 to the fingers 69 and at 72 to the arms 66, normally hold the delivery fingers 67 and 45 69 in cooperating position. The fingers 69 are provided with pins 73 which cooperate with rocking cam tracks 74 pivotally mounted at 75 on the bed frame 5. A spring 76 normally retains the cam track 74 in the position indicated in Figs. 15 and 16. Fixed 50 cam tracks 77 are disposed adjacent the lower ends of the cam tracks 74 in the path of the pins 73 so that as the arms 66 move to the position indicated in Fig. 16 the 55 fingers 69 are separated from the fingers 67. As the arms 66 move upwardly the pins 73 engage the inner faces of the cam tracks 74, thus holding the fingers 69 from engagement with the fingers 67 until the former have 60 been inserted beneath the sheet of paper above the bed plate 6. Continued movement of the arms 66 permits the pins 73 to pass the end of the cam tracks 74 whereupon the 65 fingers 69 are released and the sheet of paper is gripped between the fingers 69 and 67.

Return movement of the arms 66 causes the withdrawal of the paper from its position above the bed plate 6, the fingers 69 and 67 being separated by the engagement of the pins 73 with the fixed cam tracks 77 and the 70 paper being deposited upon a table 78 suitably supported on the bed frame 5.

The means for feeding address devices bearing names and addresses to and for supporting such devices in printing position 75 adjacent the body form 7 is bodily movable to and out of printing position so that letters or other matter without names and addresses may be printed on the machine and when desired a larger body form than that employed when names and addresses are to be printed may be mounted on the bed plate 6. The mechanism last referred to consists of a frame 79 (Figs. 17, 18 and 19) slidably mounted in suitable guideways 80 on the 80 bed frame 5 and provided with an auxiliary bed 81 adapted to support an address device adjacent the body form 7 on the bed plate 6. The frame 79 is normally locked in position by the members 82 engaging grooves 83 in 85 the frame 79 and held in position by screws 84. By loosening the screws 84 the frame 79 is released and may be moved rearwardly to withdraw the auxiliary bed 81 from its normal position.

A magazine 85 is mounted on the frame 79 and is adapted to support a plurality of address devices 86 each bearing an individual name and address. Reciprocable slides 87 are supported by members 88 slidably mounted in the frame 79 and having dogs 89 normally held by springs 90 in position to engage the lowest address device 86 in the magazine 85 and move the same forward and in a direction longitudinally of 100 the body form 7 beneath the guides 91 to position upon the auxiliary bed 81. When the address device has nearly completed its forward movement it engages projections 92 on loosely mounted auxiliary slides 93 the 105 function of which is to move the address devices in the reverse direction after an impression has been taken therefrom. The slides 93 have abutments 94 at their rearward ends adapted to be engaged by the tails of the 110 dogs 89 when the slides 87 have nearly completed their return movement. Thus it will be seen that while the slides 93 are actuated by the reciprocating movement of the dogs 89 there is considerable lost motion between 115 the parts and consequently an address device 86 on the auxiliary bed 81 will not be removed therefrom until the dogs have nearly reached the limit of their rearward travel and meanwhile an impression has been 120 taken from the address device. The address device 86 is prevented from returning along its original path by guide dogs 95 which cause the address device to move in the direction indicated by the arrow on Fig. 17 to 125 130

position in front of the slides 87 whence upon the succeeding forward movement of the slides 87 it is moved along the track 96 to a chute 97 leading to a card index drawer 5 or tray 98 in which it is packed by a packer 99 (Fig. 10) pivoted at 100 on the bed frame 8 and actuated in the manner presently to be described. In the normal operation of the machine an address device is removed 10 from the auxiliary bed 81 at each rearward movement of the slides 87 and is delivered to the drawer or tray at the next forward stroke of the slides 87 while a fresh address device is positioned upon the auxiliary bed 15 81. To support the address device in the magazine 85 after the dogs 89 have removed the lowermost address device and until the dogs 89 again return I provide a member 101 (Fig. 14) pivotally mounted at one end 20 on the bed frame 5 and having flanges 102 arranged thereon and directed upwardly beneath the magazine 85. The member 101 is disposed in the path of a shaft 103 connecting the slides 87 (Fig. 10) and is so formed 25 that as the slides 87 advance the member 101 is lifted and retained in lifted position until the slides 87 again return to their original position. The address devices 86 are, therefore, always supported by the flanges 102 30 except when the dogs 89 are positioned to pick up the lowermost address device.

Impressions are taken through a ribbon 104 carried by spools 105 and 106 which are in turn mounted in brackets 107 and 108 35 (Figs. 10, 11) movable bodily and longitudinally to the position indicated in Fig. 2 in order that the ribbon 104 may be readily withdrawn from printing position to permit inspection and replacement of the body form 7. The brackets 107 and 108 slide longitudinally on tracks 109 and 110, the former being secured to the bed frame 5 and the latter to the support 22 on the opposite side of the machine. Secured to the 40 brackets 107 and 108 are racks 111 and 112, the former engaging a pinion 113 on a shaft 114 journaled in suitable bearings in the platen bed frame 8. A pinion 115 on the opposite end of the shaft 114 meshes with 45 a pinion 116 supported thereabove which in turn meshes with the rack 112. By the arrangement just described the brackets 107 and 108, may be moved bodily and longitudinally in unison along their tracks 109 and 110 to carry the ribbon 104 evenly 50 across the bed plate 6. I provide an operating handle 117 on the bracket 107 to permit the operator to readily move the brackets 107 and 108 to the position indicated in 55 Fig. 2. A latch 118 is pivotally mounted at 119 on the handle 117 and is provided with a dog 120 normally held by a spring 121 in position to engage a pin 122 on the platen bed frame 8, thus locking the brackets 107 and 108 in normal position. The latch 118

is so formed that when the handle 117 is grasped by the operator the dog 120 is withdrawn from the pin 122.

The spools 105 and 106 are loosely journaled in bearings 123 (Fig. 4) in the inner 70 ends of the brackets 107 and 108 and at their outer ends are adapted to be engaged by members 124 mounted in the brackets 107 and 108 and pressed by springs 125 toward the ends of the spools 105 and 106. Knurled 75 heads 126 on the members 124 permit rotation of the spools 105 and 106 to wind and re-wind the ribbon 104. The opposite ends of the spools 105 and 106 are adapted to be engaged by clutch fingers 127 on shafts 80 128 rotatably mounted in suitable bearings in the platen frame 8 and provided with operating handles 129 so that the ribbon 104 may be manually wound and rewound from the feed side of the machine when the ribbon 104 is in normal position. Secured to the shafts 128 are ratchets 130 and 131 (Fig. 13) and loosely mounted on the shafts 128 are members 132 and 133 carrying pawls 134 and 135 engaging the ratchets 90 130 and 131. Springs 136 maintain the pawls 134 and 135 in engagement with the ratchets. The members 132 and 133 are connected to rods 137 and 138 extending downwardly through the bed frame 5, the rod 137 being provided with a notch 139 adapted 95 to be engaged by the end of a rocker 140 pivotally mounted on an eccentric pin 141 formed on a rotatable member 142 which is mounted on the bed frame 5 and provided 100 with an operating handle 143 (Fig. 1). By means of the operating handle 143 the rocker 140 may be shifted lengthwise to withdraw one end from operative relation to the rod 138 and engage its other end with 105 the notch 139 in the rod 137 to feed the ribbon in one direction, or to withdraw said end from operative relation to said notch and to project the other end of the rocker beneath the lower end of the rod 138 to 110 feed the ribbon in the opposite direction when the rocker is rocked as hereafter described.

To lift the ribbon 104 above the level of the printing plate 7 when it is necessary to 115 move the ribbon to the position indicated in Fig. 2 I provide a member 144 (Fig. 2) pivotally mounted on the bracket 107 and extending beneath the ribbon. The member 144 is held in its lower or normal position 120 by a spring 145 secured to a pin 146 thereon and to the bracket 107. The member 147 is rotatably mounted in the bracket 107 and is provided with an operating handle 148 and with a cam surface engaging beneath 125 the member 144 so that when the member 147 is rotated the member 144 is lifted to lift the ribbon 104 above the level of the body form 7. The opposite end of the ribbon 104 is normally maintained in proper 130

relation to the body form 7 by a member 149 (Fig. 12) extending above and transversely of the ribbon which member is pivotally mounted on the platen frame 8 and is provided with a finger-piece 150 permitting it to be moved to operative position against a spring 151 secured to a pin 152 on the platen frame 8 and to a pin 153. A latch 154 controlled by a spring 155 engages a pin 156 on the member 149 and retains it in operative position. When the member 149 is released from the latch 154 the spring 151 moves the member 149 to inoperative position so that the ribbon 104 may be withdrawn as indicated in Fig. 2.

To prevent the taking of impressions from various protuberances on the address devices 86 I provide a shield 157 (Fig. 3) having an opening 158 therein, the shield 157 being supported by an arm 159 on a pivoted member 160 which permits the shield 157 to be lifted when the ribbon 104 is to be removed. The shield 157 is disposed above the ribbon with its opening 158 registering with the portion of an address device 86 bearing a name and address. The shield 157 is constructed of thin sheet metal so that the platen 26 passes readily thereover.

The operating mechanism for the machine includes a rock arm 161 (Fig. 2) secured to a shaft 162 journaled in suitable bearings in the bed frame 5 and provided with an operating handle 163. The rock arm 161 is connected to the platen carriage 25 by a pair of links 164 so that as the arm 161 is rocked the platen carriage 25 is moved transversely of the machine. A bevel segment 165 is secured to the shaft 162 and meshes with a bevel pinion 166 loose on a stub shaft 167 supported in suitable bearings on the bed frame 5. The bevel pinion 166 is secured to sleeves 168 and 169 on the stub shaft 167, the sleeve 169 being provided with a cam 170 engaging a roller 171 on the rocker 140 (Fig. 13). The roller 171 is held in engagement with the cam 170 by a spring 172 secured to the rocker 140 and to the bed frame 5. Obviously when the arm 161 is rocked the rocker 140 will be swung on its pivot 141 to operate one or the other of the rods 137, 138 and advance the ribbon 104 in the manner previously described.

The sleeve 168 is provided with an arm 173 (Figure 12) which is connected to a lug 174 on a semi-casing 175 partially enclosing a rod 176 and a spring 177 (Figs. 8, 9). The semi-casing 175 is slidably mounted on the rod 176 which extends through the spring 177. One end of the semi-casing 175 is provided with a shoulder 178 engaging the spring 177 the other end of which rests against a shoulder 179 on a complementary semi-casing 180 fastened on the rod 176. The semi-casing 180 is provided with a lug 181 secured to an arm 181'

loosely mounted on a shaft 182' and having an opening 182 therein adapted to receive the end of a pin 183 slidably mounted in suitable bearings in a rocker 184 mounted on the shaft 182'. The pin 183 is normally pressed by a spring 186 in the direction of the arm 181' and the arm 181' is provided with a cam face 187 in the path of the end of the pin 183 so that the pin 183 will automatically enter the opening 182 to connect the operating mechanism to the rocker 184. A finger piece 188 on the pin 183 is adapted to engage an abutment 189 when the pin 183 is moved laterally against the spring 186 to release the rocker 184 from the operating mechanism.

An arm 190 of the rocker 184 (Fig. 10) is connected by a link 191 to the shaft 103 so that movement of the rocker 184 is imparted to the shaft 103 and therefore to the slides 87 upon which the dogs 89 are supported. Rollers 192 (Fig. 14) on the shaft 103 engage tracks 193 to reduce the friction as the slide is operated. A link 194 (Fig. 10) connects the rocker 184 to an arm 195 on the packer 99 which engages and moves the printing devices 86 rearwardly in the drawer or tray 98 as the rocker 184 swings rearwardly.

The arm 181' is provided with a lateral extension 196 (Fig. 7) connecting it with an arm 197 on shaft 182' (Fig. 11) at the opposite side of the machine. A link 198 is loosely mounted in the end of the arm 197 and provided with a hooked end 199 adapted to engage a notch 200 in a vertically movable rack bar 201 guided by suitable lugs on the bed frame 5. A spring 202 secured to the link 198 and to a pin 203 on the bed frame 5 normally holds the hooked end 199 of the link 198 in engagement with the notch 200. The rack bar 201 is provided with a rack 204 engaging a pinion 205 on the shaft 65 to which the arms 66 previously described are secured. When the link 198 is connected to the member 201 in the manner described the rocking of the arm 181' will reciprocate the rack bar 201 and thereby rotate the shaft 65 to actuate the arms 66, thus causing the delivery fingers 67 and 69 to pick up the paper and remove it from the machine. As it is desirable that the arms 66 be moved to inoperative position when it is necessary to move the ribbon mechanism to the position indicated in Fig. 2 I provide a rod 206 supported on the bed frame 5 and provided with a finger 207 engaging the link 198. The rod 206 extends through the bed frame 5, its end 208 being so disposed as to be readily operable to thrust the link 198 rearwardly and free it from the notch 200. The weight of the member 201 then causes the shaft 65 to rotate, withdrawing the arms 66 to the position indicated in Fig. 16. When the arm 181' is again actu-

ated the link 198 will automatically enter the notch 200 to move the arms 66 to the position indicated in Fig. 15.

The operation of the machine will be readily understood from the following brief description thereof. The operator first disposes a number of address devices 86 in the magazine 85 and arranges a supply of paper on the table 48. A body form 7 is secured to the bed plate 6 in front of the auxiliary bed 81 upon which the address devices are held during the printing operation. The ribbon 104, which is necessarily in the position indicated in Fig. 2 while the body form 7 is being disposed upon the table 6, is moved to its normal position and the members 144 and 149 are moved to the position best illustrated in Figs. 2 and 12 to permit the ribbon 104 to rest upon the body form 7 and above the auxiliary bed. The shield 157 is disposed above the ribbon 104 in the manner previously described. The pin 183 should engage the opening 182 to connect the operating mechanism with the means for feeding address devices from the magazine 85. The operator then advances the platen carriage 25 slightly and returns it to its normal position, indicated in Fig. 15, to grip the first sheet of paper. The platen carriage 25 is then advanced across the bed plate 6 carrying the sheet firmly until it engages the stops 64 when the sheet is released and rests upon the ribbon 104 in position to receive an impression. During the advance of the platen carriage 25 an address device 86 is advanced and disposed upon the auxiliary bed 81 beneath the ribbon and with the printing characters thereon beneath the opening 158 in the shield 157. During the forward movement of the platen carriage 25 the platen 26 is in its upper position so that no impression is taken. At the end of its forward stroke, however, the dog 39 engages the pin 37 thrusting the anti-friction rollers 34 into the position indicated in Fig. 16 and moving the platen 26 downwardly against its springs 36. The return movement of the platen carriage 25 carries the platen 26 across the bed plate 6 in engagement with the paper and causes an impression to be taken from the body form and the address device. Simultaneously with the return movement of the platen carriage 25 the arms 66 swing upwardly carrying the fingers 69 beneath the paper and when the platen carriage 25 has reached the limit of its return movement the delivery fingers 67 and 69 grip the paper. A second sheet of paper is already presented on the table 48 in readiness to be gripped by the feed fingers 55. Before the platen carriage 25 reaches the limit of its rearward movement the projections 92 have pushed the address device 86 from the auxiliary bed 81 from which it falls into

the track 96 in the path of the slides 87. The dogs 89 pass behind the lowermost address device 86 in the magazine 85. Upon the next forward stroke of the platen carriage 25 the printed sheet, which is held by the fingers 67 and 69, is removed and deposited on the table 78 while a fresh sheet is carried to printing position by the fingers 55. Simultaneously a fresh address device is positioned upon the auxiliary bed 81 and the address device last used is moved by the slides 87 to the chute 97 whence it falls into the drawer or tray 98 in the path of the packer 99. The cycle of operations may be repeated indefinitely.

It will here be explained that, reference being had to Figures 15 and 16, the platen roller 26 is in an elevated non-printing position when the platen carriage is traveling to the right and pulling a sheet of paper from the feed table 48 to the printing form 7. On reaching the right hand end of its travel, the platen 26 is automatically lowered into printing position through the medium of the trip 87 engaged by the part 39 as hereinbefore explained, and during the return movement of the platen carriage to the left side of the machine the platen travels over the sheet previously placed upon the printing form and an impression is made on the lower side of the sheet.

From the foregoing description of the operation of the platen carriage, it will be understood that the travel of the carriage away from the feed table is the paper feeding travel of the carriage, and the return travel or movement of the carriage is the printing travel or movement thereof. The swinging of the fingers 67 and 69 from the position shown in Figure 15 to the position shown in Figure 16 is timed to occur immediately after the platen 26 escapes from the left hand side of the printing form 7, at which time the printed sheet is freed from the pinch of the platen and printing form, and the removal of the printed sheet is affected by the swinging movement of the fingers 67 and 69 during the positioning of the new sheet, the printed sheet always being in advance of the platen carriage during its movement to the right, as viewed in Figure 15.

Should the impressions not be uniform it is an indication that the platen guiding frame 8 is not adjusted properly, with respect to the bed frame 5 and this may be readily corrected by operating the screws 13 at one or more corners of the machine. If the impression is uniform but too heavy or too light the entire platen guiding frame 8 may be readily adjusted with respect to the bed frame by operating the screw 18 by means of the knurled head 19.

During the reciprocating movement of the platen carriage 25 the ribbon 104 is ad-

vanced step by step in either direction depending upon the position of the rocker 140 so that the ribbon is not quickly exhausted by impressions of the same letters continuously in the same places thereon. The ribbon spools are readily releasable from the brackets 107 and 108 by withdrawing the members 124 so that the ribbon may be frequently reversed, thus preventing an undue amount of wear along the line of engagement of the ribbon with the address devices. When it is necessary to obtain access to the body form the ribbon 104 may be quickly moved by grasping the handle 117 and sliding the ribbon supporting mechanism bodily to the position indicated in Fig. 2.

It is frequently desirable to print circulars or other matter without addresses and accordingly I have provided, as previously explained, for the removal of the auxiliary bed 81 from the path of the platen 26. The entire mechanism for feeding address devices is moved rearwardly with the auxiliary bed 81 and the operating mechanism is separated from the mechanism for feeding the address devices by moving the finger-piece 188 into engagement with the abutment 189, thus withdrawing the pin 183 from the opening 182. It will be noted that this operation does not affect the movement of the arm 181' which is connected to the arms 66 carrying the fingers 67 and 69 and consequently the mechanism for removing the printed sheets from the machine continues in operation whether the address devices are employed or not.

While I have described the mechanism more particularly as operated by hand it is obvious that a source of power may be readily connected to the rocking arm 161 or other suitable portion of the operating mechanism and that the machine will operate with equal efficiency under the actuation of power. It is desirable that where the machine is to be operated by power a throw off be provided which is manually operable at will to prevent the movement of the platen 26 to printing position upon its return stroke, should the operator desire for any reason to prevent the taking of an impression. I therefore mount a rod 209 (Fig. 3) in a suitable guide 210 on the side of the platen frame 8 and connect it loosely with a bell-crank lever 211 having an extension 212 adapted to be moved into the path of the dog 39. A spring 213 is disposed between a collar 214 on the rod 209 and the end 215 of the bell-crank lever 211. An operating knob 216 is provided on the rod 209 whereby the latter may be forced inwardly to thrust the extension 212 into the path of the dog 40 as the platen carriage 25 starts its return stroke, thus causing the anti-friction rollers 34 to be moved

to the position indicated in Fig. 15 and permitting the platen 26 to be lifted by its springs 36.

From the foregoing description it will be understood that I have perfected a printing machine adapted for a wide variety of uses and particularly for the printing of letters simulating typewriting and bearing individual addresses. The address and body of the letter, being printed simultaneously through the same ribbon, closely resemble letters written on a typewriter and therefore receive more attention than the usual circular letter. The machine is not, however, limited to the simulation of typewritten letters since a variety of type faces may obviously be employed. Moreover it is my intention to employ the machine for printing circulars without addresses, and other matter. The movement of the platen 26 at an angle to the direction of the lines of type on the body form insures an even impression regardless of the length of individual lines of type, a difficulty inherent in printing machines employing ribbons, which I have overcome after much study and a large amount of experimental work.

It will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a printing machine, the combination of a stationary printing form having a plurality of lines of type arranged transversely thereof, an inking ribbon, means for feeding said ribbon longitudinally of said printing form, and a platen roller movable transversely of said printing form at an angle to the direction of the lines of type thereon to cause an impression to be taken through said ribbon from said printing form.

2. In a printing machine, the combination of a stationary printing form bearing a plurality of lines of type arranged transversely thereof, a magazine adapted to support a plurality of changeable printing forms, means for successively feeding changeable printing forms from said magazine to a position adjacent said stationary printing form, an inking ribbon, means for feeding said ribbon longitudinally of said stationary printing form, and a platen roller movable transversely of said printing forms at an angle to the direction of the lines of type thereon to cause an impression to be taken through said ribbon from said printing forms.

3. In a printing machine, the combination of a stationary printing form bearing a plurality of lines of type arranged transversely thereof, a magazine adapted to support a plurality of changeable printing forms,

means for moving said changeable printing forms longitudinally of said stationary printing form to and from printing position adjacent thereto, an inking ribbon disposed above said stationary printing form, means for feeding said ribbon, and a platen roller movable transversely of said printing forms at an angle to the direction of the lines of type thereon to cause an impression to be taken through said ribbon from said printing forms.

4. In a printing machine, the combination of a stationary printing form bearing a plurality of lines of type arranged transversely thereof, a magazine adapted to support a plurality of changeable printing forms, reciprocable means movable longitudinally of said stationary printing form to move said changeable printing forms from said magazine to and from printing position adjacent said stationary printing form, an inking ribbon disposed above said stationary printing form, and a platen roller movable transversely of said stationary printing form to cause an impression to be taken through said ribbon from said printing forms.

5. In a printing machine, the combination of a stationary printing form bearing a plurality of lines of type, a magazine adapted to support a plurality of changeable printing forms, a bed adjacent said stationary printing form, reciprocable means movable longitudinally of said stationary printing form to successively move said changeable printing forms from said magazine to said bed, means actuated by said reciprocable means when moving in an opposite direction to successively remove said changeable printing forms from said bed, an inking ribbon disposed above said stationary printing form and bed, and a bodily movable platen roller to cause impressions to be taken through said ribbon from said printing forms.

45 6. In a printing machine, the combination of a stationary printing form bearing a plurality of lines of type, a magazine adapted to support a plurality of changeable printing forms, a bed adjacent said stationary printing form, reciprocable means movable longitudinally of said stationary printing form to successively move said changeable printing forms from said magazine to said bed, means actuated by said reciprocable means when moving in an opposite direction to successively remove said changeable printing forms from said bed, an inking ribbon disposed above said stationary printing form and bed, a bodily movable platen roller to cause impressions to be taken through said ribbon from said printing forms, and a shield above said ribbon and bed provided with an opening through which impressions from said changeable printing forms are secured.

7. In a printing machine, the combination of a stationary printing form bearing a plurality of lines of type, a magazine adapted to support a plurality of changeable printing forms, a bed adjacent said stationary printing form, reciprocable means movable longitudinally of said stationary printing form to successively move said changeable printing forms from said magazine to said bed, means actuated by said reciprocable means when moving in an opposite direction to successively remove said changeable printing forms from said bed, an inking ribbon disposed above said stationary printing form and bed, means for advancing said ribbon longitudinally of said bed, a bodily movable platen roller, and means for moving said platen roller at an angle to the direction of the lines of type on said stationary printing form to cause impressions to be taken through said ribbon from said printing forms.

8. In a printing machine, the combination of a stationary printing form, a bed adjacent said stationary printing form, a magazine adapted to support a plurality of changeable printing forms, reciprocable means for successively moving changeable printing forms from said magazine to said bed, a track beneath said bed, and means actuated by said reciprocable means when moving in an opposite direction for delivering changeable printing forms from said bed to said track.

9. In a printing machine, the combination of a stationary printing form, a bed adjacent said stationary printing form, a track beneath said bed, a magazine adapted to support a plurality of changeable printing forms, reciprocable slides having means for successively moving changeable printing forms from said magazine to said bed, and means actuated by said reciprocable means when moving in an opposite direction for delivering said changeable printing forms from said bed to said track.

10. In a printing machine, the combination of a stationary printing form, a bed adjacent said stationary printing form, a track beneath said bed, a magazine adapted to support a plurality of changeable printing forms, reciprocable means for successively moving changeable printing forms from said magazine to said bed, means actuated by said reciprocable means when moving in an opposite direction for delivering said changeable printing forms from said bed to said track, a drawer or tray, and a chute leading from said track to said drawer or tray.

11. In a printing machine, the combination of a stationary printing form, a bed adjacent said stationary printing form, a track beneath said bed, a magazine adapted to support a plurality of changeable print-

- ing forms, reciprocable means for successively moving changeable printing forms from said magazine to said bed, means actuated by said reciprocable means when moving in an opposite direction for delivering said changeable printing forms from said bed to said track, a drawer or tray, a chute leading from said track to said receiving magazine, and a packer in said drawer or tray.
12. In a printing machine, the combination of a stationary printing form having a plurality of lines of type, a bed adjacent said stationary printing form, a track beneath said bed, a magazine adapted to support a plurality of changeable printing forms, reciprocable means for successively moving changeable printing forms from said magazine to said bed, means actuated by said reciprocable means when moving in an opposite direction for delivering said changeable printing forms from said bed to said track, a ribbon above said stationary printing form and bed, and a platen roller for causing impressions to be taken through said ribbon from said printing forms.
13. In a printing machine, the combination of a stationary printing form having a plurality of lines of type, a bed adjacent said stationary printing form, a track beneath said bed, a magazine adapted to support a plurality of changeable printing forms, reciprocable means for successively moving changeable printing forms from said magazine to said bed, means actuated by said reciprocable means when moving in an opposite direction for delivering said changeable printing forms from said bed to said track, a ribbon above said stationary printing form and bed, and a platen roller movable across said stationary printing form at an angle to the direction of the lines of type thereon to cause impressions to be taken from said printing forms.
14. In a printing machine, the combination of a stationary printing form having a plurality of lines of type, a bed adjacent said stationary printing form, a track beneath said bed, a magazine adapted to support a plurality of changeable printing forms, reciprocable means for successively moving changeable printing forms from said magazine to said bed, means actuated by said reciprocable means when moving in an opposite direction for delivering said changeable printing forms from said bed to said track, a ribbon above said stationary printing form, means for advancing said ribbon longitudinally of said stationary printing form and bed, and a platen roller movable transversely of said stationary printing form to cause impressions to be taken through said ribbon from said printing forms.
15. In a printing machine, the combination of a stationary printing form, a bed adjacent said stationary printing form, a magazine adapted to support a plurality of changeable printing forms, and means for moving changeable printing forms from said magazine to said bed, said bed, magazine and last-mentioned means being separable as a unit from said stationary printing form.
16. In a printing machine, the combination of a stationary printing form, a platen roller movable across said stationary printing form, a bed adjacent said stationary printing form in the path of said platen, a magazine adapted to support a plurality of changeable printing forms, and means for successively moving changeable printing forms from said magazine to said bed, said bed, magazine and last-mentioned means being movable as a unit with respect to said stationary printing form to remove said bed from the path of said platen roller.
17. In a printing machine, the combination of a bed frame, a stationary printing form supported thereon, a platen roller movable across said stationary printing form, a ribbon between said platen roller and stationary printing form, guideways on said bed frame, an auxiliary frame supported on said guideways, a bed, a magazine adapted to support a plurality of changeable printing forms and means for successively moving said changeable printing forms from said magazine to said bed, said bed, magazine and means being supported on said auxiliary frame, and means for detachably securing said auxiliary frame on said bed frame with said bed adjacent said stationary printing form.
18. In a printing machine, the combination of a bed frame, a stationary printing form supported thereon, a platen roller movable across said stationary printing form, a ribbon between said platen roller and stationary printing form, guideways on said bed frame, an auxiliary frame supported on said guideways, a bed, a magazine adapted to support a plurality of changeable printing forms and means for successively moving said changeable printing forms from said magazine to said bed, said bed, magazine and means being supported on said auxiliary frame, means for detachably securing said auxiliary frame on said bed frame with said bed adjacent said stationary printing form, means for actuating said platen roller, and means for detachably connecting said actuating means with the means for successively moving changeable printing forms.
19. In a printing machine, the combination of a bed frame, a printing form thereon, a platen guiding frame, a platen supported thereby, springs on said bed frame supporting said platen guiding frame, bolts

- connected to said platen guiding frame and extending through said bed frame, and rock shafts connected to said bolts for adjusting said platen guiding frame relatively to the 5 bed frame.
20. In a printing machine, the combination of a bed frame, a printing form thereon, a platen guiding frame, a platen supported thereby, springs on said bed frame 10 supporting said platen guiding frame, bolts connected to said platen guiding frame and extending through said bed frame, shafts journaled in said bed frame having eccentric pins connected to said bolts, and means 15 for rocking said shafts to adjust said frames relatively to each other.
21. In a printing machine, the combination of a bed frame, a printing form thereon, a platen guiding frame, a platen supported thereby, springs on said bed frame 20 supporting said platen guiding frame, bolts connected to said platen guiding frame and extending through said bed frame, shafts journaled in said bed frame having eccentric 25 pins connected to said bolts, a link connecting said shafts, and a screw device engaged with said link for simultaneously rocking the shafts to adjust said frames relatively to each other.
30. 22. In a printing machine, the combination of a stationary printing form, a magazine adapted to support a plurality of changeable printing forms, means for successively moving changeable printing forms 35 from said magazine to printing position adjacent said printing form, a ribbon, a platen carriage movable across said stationary printing form, a platen carried thereby, and means on said carriage to automatically engage both sides of a sheet of paper and position it above said stationary printing form.
23. In a printing machine, the combination of a stationary printing form, a magazine adapted to support a plurality of 40 changeable printing forms, means for successively moving changeable printing forms, from said magazine to printing position adjacent said printing form, a ribbon, a platen carriage movable across said stationary printing form, a platen carried thereby, means on said carriage to automatically engage both sides of a sheet of paper and position it above said stationary printing form, and means to automatically remove the 45 paper after impression is made thereon.
24. In a printing machine, the combination of a stationary printing form, a magazine adapted to support a plurality of changeable printing forms, means for successively moving changeable printing forms 50 from said magazine to printing position adjacent said stationary printing form, a ribbon, a platen carriage movable across said stationary printing form, a platen carried thereby, and means on said carriage to automatically pick up a sheet of paper and position it above said stationary printing form to 55 thereby, and means on said carriage to automatically pick up a sheet of paper and position it above said stationary printing form and position it above said stationary printing form.
25. In a printing machine, the combination of a stationary printing form, a magazine adapted to support a plurality of changeable printing forms, means for successively moving changeable printing forms from said magazine to printing position adjacent said stationary printing form, a ribbon, a platen carriage movable across said stationary printing form, a platen carried thereby, means on said carriage to automatically pick up a sheet of paper and position it above said stationary printing form, and means to automatically remove the paper after an impression is secured thereon.
26. In a printing machine, the combination of a stationary printing form, a magazine adapted to support a plurality of changeable printing forms, means for successively moving changeable printing forms from said magazine to printing position adjacent said stationary printing form, a ribbon, a platen carriage movable across said stationary printing form, a platen carried thereby, a feed table, grippers on said carriage to automatically pick up a sheet of paper from said feed table and position it above said stationary printing form upon the forward movement of said carriage, and means to automatically remove the paper after an impression is secured thereon.
27. In a printing machine, the combination of a stationary printing form, a magazine adapted to support a plurality of changeable printing forms, means for successively moving changeable printing forms from said magazine to printing position adjacent said stationary printing form, a ribbon, a platen carriage movable across said stationary printing form, a platen carried thereby, a feed table, grippers on said carriage to automatically pick up a sheet of paper and position it above said stationary printing form upon the forward movement of said carriage, and means for adjusting said platen to cause an impression to be taken upon the return movement of said carriage.
28. In a printing machine, the combination of a frame, a platen carriage movable across said frame, a feed table and means on said carriage to pick up a sheet of paper from said table including a ledge fixedly connected and held from movement relative to said carriage and fingers cooperating with said ledge, and means for lifting said fingers as said carriage approaches said table.
29. In a printing machine, the combina-

- tion of a frame, a platen carriage movable across said frame, a feed table, guides in front of said table against which the paper rests, and means on said carriage to pick up a sheet of paper from said table including a ledge fixedly connected and held from movement relative to said carriage and spring-pressed fingers cooperating with said ledge, and means on said frame to cause said fingers to be lifted as said carriage approaches said table and subsequently released to grip the paper.
30. In a printing machine, the combination of a frame, a platen carriage movable across said frame, a feed table, guides in front of said table against which the paper rests, and means on said carriage to pick up a sheet of paper from said table including a ledge fixedly connected and held from movement relative to said carriage, a shaft above said ledge, fingers on said shaft cooperating with said ledge, a spring to resiliently press said fingers toward said ledge and an arm on said shaft, and means on said frame adapted to be engaged by said arm to cause said fingers to be lifted as said carriage approaches said table and subsequently released to grip the paper.
31. In a printing machine, the combination of a stationary printing form, a ribbon above said printing form, a platen carriage movable transversely of said printing form, a platen supported by said carriage, a feed table, means on said carriage to pick up a sheet of paper from said feed table and move it across said printing form, and stops disposed in the path of the paper to prevent movement thereof beyond printing position.
32. In a printing machine, the combination of a stationary printing form, a ribbon above said printing form, a platen carriage movable transversely of said printing form, a platen supported by said carriage, a feed table, means on said carriage to pick up a sheet of paper from said feed table and move it across said printing form, stops disposed in the path of the paper to prevent movement thereof beyond printing position, and means for removing the paper from printing position after an impression has been received thereon.
33. In a printing machine, the combination of a printing form, a ribbon, a platen movable across said printing form and ribbon, and means for removing a sheet of paper from printing position including a rock shaft, relatively movable delivery fingers carried by said shaft, and movable means for guiding said fingers into position to engage a sheet.
34. In a printing machine, the combination of a printing form, a ribbon, a platen movable across said printing form and ribbon, and means for removing a sheet of paper from printing position including a rock shaft, relatively movable delivery fingers carried by said shaft, and movable means for supporting said ribbon above said printing form and guides for said means to permit bodily movement thereof in a horizontal plane to remove said ribbon from said printing form.
35. In a printing machine, the combination of a printing form, a ribbon, a platen movable across said printing form and ribbon, and means for removing a sheet of paper from printing position including a rock shaft, relatively movable delivery fingers carried by said shaft, means for separating said fingers, and movable means for guiding said separated fingers into position to engage a sheet.
36. In a printing machine, the combination of a printing form, a ribbon, a platen movable across said printing form and ribbon, means for removing a sheet of paper from printing position above said ribbon, including a shaft, arms secured thereto, relatively movable fingers supported by said arms and resiliently biased toward each other, means for rocking said shaft to swing said arms toward the paper in printing position, actuating means therefor, means to separate said fingers and to subsequently permit them to engage the paper and means to release the paper from said fingers after it has been withdrawn, and a manually releasable connection between said rocking and actuating means.
37. In a printing machine, the combination of a printing form, a ribbon, a platen movable across said printing form and ribbon, and means for removing a sheet of paper from printing position above said ribbon including a shaft, means for rocking said shaft, arms secured to said shaft, rigid and movable fingers supported on said arms, springs normally holding said movable fingers in engagement with said rigid fingers, pins on said movable fingers, pivoted cam tracks in the path of movement of said pins, whereby said movable fingers are held from engagement with said rigid fingers and subsequently released to grip the paper, and fixed cam tracks in the path of movement of said pins whereby said movable fingers are separated from said rigid fingers to release the paper.
38. In a printing machine, the combination of a printing form, a ribbon, a platen movable across said printing form and ribbon, means for removing a sheet of paper from printing position above said ribbon, actuating mechanism therefor, and a manually releasable connection between said means and mechanism.
39. In a printing machine, the combination of a printing form, a ribbon, means for supporting said ribbon above said printing form and guides for said means to permit bodily movement thereof in a horizontal plane to remove said ribbon from said printing form.

40. In a printing machine, the combination of a printing form, a ribbon, and means for supporting said ribbon in printing position above said printing form including spools and separate brackets supporting said spools, said brackets being movable longitudinally to withdraw said ribbon from printing position.
41. In a printing machine, the combination of a printing form, supports at either end thereof, brackets slideable on said supports, spools carried by said brackets, and a ribbon on said spools, said brackets being movable to withdraw said ribbon from printing position above said printing form.
42. In a printing machine, the combination of a printing form, supports at either end thereof, brackets slideable on said supports, spools carried by said brackets, a ribbon on said spools, and a connection between said brackets whereby movement of one is transferred to the other.
43. In a printing machine, the combination of a printing form, supports at either end thereof, brackets slideable on said supports, spools carried by said brackets, a ribbon on said spools, racks secured to said brackets, a shaft, a pinion at one end of said shaft engaging one of said racks, a pinion at the other end of said shaft, and an intermediate pinion between the last-mentioned pinion and the other of said racks.
44. In a printing machine, the combination of a frame, a printing form, a ribbon, means for supporting said ribbon above said printing form, guides for said means to permit bodily movement thereof in a horizontal plane to remove said ribbon from said printing form, and means on said frame to advance said ribbon across said printing form when the former is disposed in printing position.
45. In a printing machine, the combination of a frame, a printing form, supports at either end of said frame, spool brackets slideable on said supports, spools carried by said spool brackets, a ribbon on said spools, said spool brackets being longitudinally slideable to withdraw said ribbon from printing position above said printing form, and means on said frame to advance said ribbon across said printing form when said ribbon is disposed in printing position.
46. In a printing machine, the combination of a frame, a printing form, a ribbon above said printing form, spools for supporting said ribbon, and means for rotating said spools to wind said ribbon including ratchets connected to said spools, pawls cooperating with said ratchets, rods connected to said pawls, a rocker adapted for engagement directly with one or the other of said rods, and means for actuating said rocker.
47. In a printing machine, the combination of a frame, a printing form, a ribbon above said printing form, spools for supporting said ribbon including ratchets connected to said spools, pawls cooperating with said ratchets, rods connected to said pawls, a rocker adapted for engagement directly with one or the other of said rods, means for actuating said rocker, and means for shifting said rocker whereby the direction of movement of said ribbon may be varied.
48. In a printing machine, the combination of a frame, a printing form thereon, supports at either end of said printing form, brackets slideably mounted on said supports, and spools removably mounted on said brackets, said brackets being longitudinally movable to permit withdrawal of said ribbon from printing position above said printing form.
49. In a printing machine, the combination of a frame, a printing form thereon, supports at either end of said printing form, brackets slideably mounted on said supports, spools removably mounted on said brackets, said brackets being longitudinally movable to permit withdrawal of said ribbon from printing position above said printing form, and means for locking said brackets when said ribbon is disposed in printing position.
50. In a printing machine, the combination of a bed frame, a stationary printing form supported thereon, a magazine adapted to hold a plurality of changeable printing forms, reciprocable means for moving changeable printing forms from said magazine to printing position adjacent said stationary printing form, a platen carriage, a platen roller supported thereon, actuating means for said platen carriage, reciprocable means including a rocker arm connected to said platen carriage, and a releasable connection between said rocker arm and reciprocable means.
51. In a printing machine, the combination of a bed frame, a stationary printing form supported thereon, a magazine adapted to hold a plurality of changeable printing forms, reciprocable means for moving changeable printing forms from said magazine to printing position adjacent said stationary printing form, a platen carriage, a platen roller supported thereon, actuating means for said platen carriage, reciprocable means including a rocker arm connected to said platen carriage, and a resilient connection between said rocker arm and reciprocable means.
52. In a printing machine, the combination of a platen guiding frame, a platen carriage mounted thereon, a platen roller supported by said carriage, tracks on said frame, grooved rollers rotatable with said platen roller, and flanged rollers between said grooved rollers and said tracks, the

flanges of said rollers engaging said tracks and said grooved rollers engaging said flanged rollers on either side of the flanges thereon.

- 5 53. In a printing machine, the combination of a printing form, a platen guiding frame, a platen carriage mounted thereon, a platen roller mounted to swing on said carriage toward and from said printing form, 10 a spring normally holding said platen roller away from said printing form, and means for moving said platen roller to printing position adjacent said printing form including rollers mounted concentrically with said 15 platen roller, tracks on said platen guiding frame, and rollers adapted to be positioned between said tracks and the concentrically mounted rollers.

54. In a printing machine, the combination 20 of a printing form, a platen guiding frame, a platen carriage mounted thereon, a platen roller mounted to swing on said carriage toward and from said printing form, a spring normally holding said platen roller 25 away from said printing form, and means for moving said platen roller to printing position adjacent said printing form including rollers mounted concentrically with said platen roller, tracks on said platen guiding 30 frame, rollers adapted to be positioned between said tracks and the concentrically mounted rollers, and means on said platen frame and on said carriage to automatically move the track-engaging rollers to and from 35 operative position.

55. In a printing machine, the combination 40 of a magazine adapted to support a plurality of changeable printing forms, a drawer or tray to receive said changeable printing forms, a fixed bed between said magazine and tray to support said changeable printing forms in printing position, and means for successively moving said changeable printing forms from said magazine to said drawer or tray in three steps, one of said steps requiring movement in the 45 reverse direction to the other steps.

56. In a printing machine, the combination 50 of a magazine adapted to support a plurality of changeable printing forms, a fixed bed to successively support said changeable printing forms in printing position, and means for moving said changeable printing forms to and from said bed including 55 means for imparting an intermediate movement to said changeable printing forms from said bed toward said magazine.

57. In a printing machine, the combination 60 of a magazine adapted to support a plurality of changeable printing forms, a fixed bed to successively support said changeable printing forms in printing position, and reciprocable means for moving said changeable printing forms forwardly from said magazine and to and from said bed, and

means for imparting an intermediate rearward and downward movement to said changeable printing forms.

58. In a printing machine, the combination of a magazine adapted to support a plurality of changeable printing forms, a fixed bed to successively support a changeable printing form in printing position, a drawer or tray to receive said changeable printing form, reciprocable means for moving a 70 changeable printing form from a position rearwardly of said bed to said drawer or tray and a succeeding changeable printing form from said magazine to said bed at each forward movement of said reciprocable means, and means for moving said succeeding changeable printing form rearwardly from said bed as said reciprocable means returns to its initial position.

59. In a printing machine, the combination 75 of a magazine adapted to support a plurality of changeable printing forms, a bed to successively support a changeable printing form in printing position, a drawer or tray to receive said changeable printing form, reciprocable means for moving a 80 changeable printing form from a position rearwardly of said bed to said drawer or tray and a succeeding changeable printing form from said magazine to said bed at 85 each forward movement of said reciprocable means, means for moving said succeeding changeable printing form rearwardly from said bed as said reciprocable means returns to its initial position, a stationary printing 90 form adjacent said bed, a ribbon above said stationary printing form and bed, a platen roller adapted to travel over said stationary printing form, and means for actuating said platen roller and reciprocable means in 95 unison.

60. In a printing machine, the combination 100 of a stationary printing form having a plurality of lines of type arranged transversely thereof, an inking ribbon above said form, and a platen roller movable transversely of said printing form at an angle to the direction of the lines of type thereon to cause an impression to be taken through 105 said ribbon from said printing form.

61. In a printing machine, the combination 110 of a bed frame, a printing form, a ribbon, a platen guiding frame, a carriage reciprocally movable in said platen guiding frame, a platen on said carriage, and means operating with a wedge action between the platen guiding frame and the platen to depress the platen into operative relation with 115 said printing form.

62. In a printing machine, the combination 120 of a bed frame, a printing form, a ribbon, a platen guiding frame, a platen carriage reciprocally movable in said platen guiding frame, a platen roller yieldingly supported by said carriage, and means oper- 125

ating with a wedge action to depress the platen roller into operative relation with said printing form.

63. In a printing machine, the combination of a main frame, a printing form, a ribbon, a platen guiding frame, a platen carriage reciprocally movable in said platen guiding frame, a platen yieldingly supported by said carriage, means on the carriage for feeding a sheet of paper to the printing form, means independent of the carriage for taking the printed sheet from the form, and means for depressing said platen on its printing stroke to operatively engage the form.

64. In a printing machine, the combination of a magazine adapted to support a plurality of changeable printing forms, means for moving said printing forms forward one at a time from the magazine to printing position, means for moving the printing form rearward from printing position and to a lower plane, and means for again moving said printing form forward.

65. In a printing machine, the combination of a magazine adapted to support a plurality of changeable printing forms, conjointly operating means for moving said printing forms one at a time from said magazine to printing position and at the same time moving a printing form which has been discharged from printing position, and means for discharging the printing form from printing position.

66. In a printing machine, the combination of a magazine adapted to support a plurality of changeable printing forms, means operating conjointly for moving said printing forms forward one at a time in successive operations and in different planes, and means for moving the printing form between said successive operations.

67. In a printing machine, the combination of a frame, a printing form thereon, and means for supporting a ribbon above said form, said supporting means being slidably movable to withdraw the ribbon from operative position above the form.

68. In a printing machine, the combination of a frame, a printing form thereon, means for supporting an inking ribbon above said form, and ribbon feeding means, said supporting means being slidably movable transversely of the direction of feed of the ribbon to withdraw the ribbon from operative position above the form.

69. In a printing machine, the combination of a frame, a printing form thereon, means for supporting an inking ribbon above said form, ribbon feeding means, and a platen mounted to move over the ribbon transversely of the direction of feed thereof, said supporting means being slidably mov-

able in a horizontal plane transversely of the direction of feed of the ribbon to withdraw the ribbon from operative position above the form.

70. In a printing machine, the combination of a frame, a printing form thereon, and means for supporting an inking ribbon above said form, said supporting means comprising a pair of ribbon rollers located at opposite ends of the form and slidably movable transversely of the frame to withdraw the ribbon from operative position above the form.

71. In a printing machine, the combination of a frame, a printing form thereon, means for supporting an inking ribbon above said form, said supporting means being slidably movable transversely of the frame to withdraw the ribbon from operative position above the form and a device for locking the supporting means in operative position.

72. In a printing machine, the combination of a frame, a printing form thereon, and means for supporting a ribbon above said form, said supporting means being slidably movable transversely of the frame to withdraw the ribbon from operative position above the form and comprising a pivoted latch device for locking the supporting means in operative position.

73. In a printing machine, the combination of a frame, a printing form, an inking ribbon, and means whereby said ribbon may be slidably moved to one side of the printing form to uncover and expose the latter.

74. In a printing machine, the combination of a frame, a printing form, an inking ribbon, a ribbon support, a slideway for said ribbon support and extending across the ends and beyond one side of the printing form, and means for moving the ribbon support along the slideway to and from printing position to cover and uncover the printing form.

75. In a printing machine of the class described, the combination of a form of type and a roller platen mounted to reciprocate transversely across the form of type in the general direction of the lines of type with the axis of the platen at slightly less than a right angle to the lines of type.

76. In a printing machine of the class described, the combination of a form of type, a guideway extending transversely across the form of type in the general direction of the lines of type but at a slight inclination thereto, and a roller platen mounted for bodily reciprocation in said guideway and across the form of type.

JOSEPH S. DUNCAN.
